UNITED STATES PATENT OFFICE.

ISIDORE ASH, OF NEW YORK, N. Y.

DESIGN FOR COMBINED OVERBLOUSE AND SASH.

60,121.

Specification for Design.

Patented Jan. 3, 1922.

Application filed August 18, 1921. Serial No. 493,454. Term of patent 7 years.

To all whom it may concern:

Be it known that I, ISIDORE ASH, a citizen of the United States, residing at New York City, county of New York, and State of New York, have invented a new, original, and ornamental Design for a Combined Overblouse and Sash, of which the following is a specification, reference being had to the accompanying drawings, forming part thereof.

Fig. 1 is a three-quarters front view and Fig. 2 a three-quarters back view of a model wearing a costume including a combined overblouse and sash incorporating the de-

sign. In the costume illustrated in the drawings the over-blouse and sash is shown worn over a waist of the same color and shade, but this waist constitutes no part of the design.

I claim:

The ornamental design for a combined over-blouse and sash, as shown.

ISIDORE ASH.
